UNITED STATES PATENT OFFICE.

JOHN R. HOUTS, OF WASHINGTON, DISTRICT OF COLUMBIA, ASSIGNOR OF
ONE-FOURTH TO SAMUEL BRUCKHEIMER, OF SAME PLACE.

PERMUTATION-PADLOCK.

SPECIFICATION forming part of Letters Patent No. 593,892, dated November 16, 1897.

Application filed May 25, 1896. Serial No. 592,989. (No model.)

To all whom it may concern:

Be it known that I, JOHN R. HOUTS, a citizen of the United States, residing at Washington, in the District of Columbia, have invented certain new and useful Improvements 5 in Permutation - Locks; and I do hereby declare the following to be a full, clear, and exact description of the invention, such as will enable others skilled in the art to which it app-10 pertains to make and use the same.

My present invention relates to improvements in permutation-locks; and the objects are to provide an efficient and durable lock of few mechanical parts which will be suit-15 able for general use and to make the opening and closing of said lock dependent upon the knowledge of the proper combination of the rotary tumblers with which it is provided.

It consists, essentially, of an outer protect-20 ive casing or lock-body, an inner latch-body containing all the mechanism, a latch carried by the said inner latch-body, and means for actuating the latch-body, whereby the latch will be forced into and out of engagement 25 with the part designed to receive it, and for locking the said inner latch-body in either position assumed by it.

In the accompanying drawings, fully illustrating my invention, Figure 1 is a sectional 30 view of the lock, showing the parts in locked engagement. Fig. 2 is a similar view showing the parts in the position they assume when the latch is out of engagement. Fig. 3 is a side elevation of the lock. Fig. 4 is a 35 detail perspective view of the rotary tumblers and spindle. Fig. 5 is a sectional view of the lock, showing the same applied to the steering-post tube of a bicycle; and Fig. 6 is a sectional view showing the application to a window-dow-sash.

Like numerals of reference designate like parts throughout all the figures of the drawings.

In constructing my lock I form it in two 45 main parts—an outer protective casing or lock-body 1 and an inner movable latch-body 2. The outer casing or lock-body in form may be as shown in Figs. 1 and 2, with a cylindrical portion 3 and opposite flat inclosing 50 sides 4 and provided interiorly with the angular partition 5, or it may be constructed of

such shape as suits the exigencies of the use to which the lock is placed, the requirement being that the casing shall comprise two flat sides, an angular side or partition, and an inclosing circular side. Within this space is 55 inclosed the latch-body 2, and this is supplied with a latch or latch-bolt 6, adapted to engage with a hasp 7, pivotally attached to the outer casing 1. This movable latch-body 2 is con-60 fined within the interior chamber or compartment formed by the smaller angle of the partition 5, and sufficient concentric movement is to be accorded the latch-body 2 to permit the complete disengagement of the latch 6 from 65 the perforation 6^a of the lock-hasp.

The latch-body 2 is preferably formed in two sections riveted or otherwise secured together, as at 7^a 7^b 7^c, and journaled between them is a spindle or tumbler-shaft 8. It projects through a slot 9 in the cylindrical portion of the outer casing 1 and is provided a little distance from it with a dial 10. Interposed between this dial and the casing or lock-body 1 and secured to a tubular shaft surrounding the spindle or shaft 8 is a second and larger dial 11. These dials are marked in a suitable manner for a purpose which will become more apparent from the description which is to follow. 80

The tubular shaft, which I will designate as 12, is of a length sufficient to carry the two tumblers 13, which said tumblers are spaced apart and keyed to the shaft. The shaft 8 is sufficiently longer than the tubular shaft 85 12 to carry the two tumblers 14, which are likewise spaced from each other and from the first-named tumblers and are also keyed to their shaft. These tumblers 13 and 14 are approximately of the same diameter and are 90 provided with the notches 15, designed to register or be revolved into alinement with each other when the predetermined marks upon the two dials exactly register. As the dials 10 and 11 may be provided with a large 95 number of marks designed to be combined at pleasure, it is apparent that unless the correct combination is known the several notches cannot be alined without considerable difficulty, and to decrease the possibility of the 100 combination becoming known it is desirable that the dial 10 or the dial 11 be so mounted

on its shaft that by the exertion of a certain amount of force it may be revolved any number of points on the said shaft, thus destroying the old combination and creating a new.

5 The tumblers 13 and 14 are designed to interlock with a curved fence 16 at one end thereof, where the same is formed with teeth 17. When the notches 15 of the several tumblers 13 and 14 are in exact alinement with 10 each other and with the teeth 17 of the fence, the latter is at liberty to be actuated back and forth in the slot 18, in which it is seated.

At an angle to the slot 18 and leading into the same is a short curved slot 19, which is 15 designed to receive a curved slidable bolt 20 of somewhat greater length than that of the slot. One end of this bolt rests against the partition 5, while the other projects into a curvature in the fence 16. This curvature 20 conforms to the curvature of the contiguous portion of the bolt 20, and the latter gradually seats itself therein and forces the fence 16 against the partition 5 when the latch-body 2 is moved in a direction to disengage the 25 latch 6. It will be remembered, however, that such movement of the latch-body 2 is dependent upon the exact alinement of the notches of the several rotary tumblers and the teeth of the curved fence 16. When in 30 this position, (indicated in Fig. 2 of the drawings,) the alinement may be destroyed and the fence 16 again locked, thus preventing a locking of the hasp. By restoring the alinement of the notches the latch-body 2 may be moved 35 forward, the fence 16 returned to its normal position, as shown in Fig. 1, and the bolt 20 will then prevent the backward movement of the latch-body 2, provided, of course, the alinement of the notches in the tumblers is 40 destroyed. In either position the fences when locked by the tumblers prevent the movement of the latch-body 2, which carries the latch.

In Fig. 5 of the drawings I have shown the 45 lock applied to the steering-post tube of a bicycle. In this case I will construct the outer casing 1, as shown, with the side walls, the angular wall, and the circular wall and will seat the same on the cross-tubing, to which 50 and the steering-post tube it will be securely fastened by a clip or by rivets, and the latch-bolt will engage with a recess 22, bored in the steering-post 23 of the bicycle, and it will be so situated that the front wheel will be locked 55 at an angle to the rear wheel, thus preventing the propulsion of the bicycle in a straight line and necessitating its carriage where larceny of the same is intended.

Fig. 6 illustrates an application of the lock 60 to a window-sash. In this construction I employ the same mechanism as in Fig. 1, with the exception of the hasp. The formation of the outer casing in halves, one for the upper sash and the other for the lower, is the only 65 difference. The upper-sash section is provided with a recess 24 to receive the latch-bolt, and the lower-sash section carries the

70 latch-body 2 and its mechanism for actuating the latch and locking it in its forward or rear position.

This completes the construction of my lock, 75 and its operation will be fully apparent from the foregoing description.

I do not desire to limit myself to the precise details of construction herein shown and described nor to the formation or precise construction of the outer casing, but reserve to myself the right and privilege to alter or change the same within the bounds of mechanical ingenuity without departing from 80 the spirit of the invention.

Having thus described my invention, what I claim as new, and desire to secure by Letters Patent, is—

1. In a lock of the character described, the 85 combination with a lock-body, having an angular chamber, of a latch-body pivotally seated in the angle of said chamber, and adapted to be swung from wall to wall of said chamber, a latch borne by said latch-body, and designed to be moved, by the latch-body, into and out of engagement with the part to be locked, a reciprocating fence working in said latch-body, a bolt also working in said latch-body and engaging with said fence to secure the 90 latch-body against either wall of the angular chamber, and means for reciprocating said fence.

2. In a lock of the character described, the 95 combination with a lock-body, having an angular chamber, of a latch-body pivotally seated in the angle of said chamber, and adapted to be swung from wall to wall of said chamber, a latch borne by said latch-body, and designed to be moved by the latch-body, into and out of engagement with the part to be locked, a reciprocating fence working in said latch-body, a bolt also working or reciprocating in 105 said latch-body and engaging with said fence, to secure the latch-body against either wall 110 of the angular chamber, the tumbler-shaft provided with notched tumblers, engaging with the fence, the tubular shaft fitting on said tumbler-shaft, having notched tumblers also engaging with the fence, and dials on the 115 outer ends of the said shafts.

3. In a lock of the character described, the 120 combination with a lock-body, having an angular chamber, of a latch-body pivotally seated in the angle of said chamber, and adapted to be swung from wall to wall of said chamber, a latch borne by said latch-body and designed to be moved by the same, into and out of engagement with the part to be locked, a curved slot in said latch-body, a notched, reciprocating fence working in said slot, a second curved slot branching from said first-named slot, a bolt working therein and engaging with a shoulder on said fence, whereby 125 the latch-body may be secured against either 130 wall of the angular chamber, and means for reciprocating said fence.

4. In a lock, the combination with a lock-body, having an angular chamber, of a latch-

body, pivotally seated in the angle of said chamber, and adapted to be swung from wall to wall of said chamber, a latch borne by said latch-body and designed to be moved by the same into and out of engagement with the part to be locked, a curved slot in said latch-body, a notched, reciprocating fence working in said slot, a second curved slot, branching from said first-named slot, a bolt working therein and engaging with a shoulder formed on said fence, whereby the latch-body may be secured against either wall of the angular chamber, the tumbler-shaft provided with notched tumblers, engaging with the fence, the tubular shaft fitting on said tumbler-shaft, having notched tumblers also engaging with the fence, and permutation-dials on the ends of said shafts, outside the lock-body, through a slot in which the said shafts project or extend.

5. The combination with a bicycle-frame and a recessed steering-post, of a lock-body secured thereto and having an angular chamber, a latch-body pivotally seated in the angle of said chamber, and adapted to be swung from wall to wall thereof, a latch borne by said latch-body and designed to be moved by the latch-body into and out of engagement with the recess in the steering-post, a reciprocating fence working in said latch-

body, a bolt also working in said latch-body and engaging with said fence, to secure the latch-body against either wall of the chamber, and means for reciprocating said fence.

6. The combination with a bicycle-frame 35 and a recessed steering-post, of a lock-body secured thereto and having an angular chamber, a latch-body pivotally seated in the angle of said chamber, and adapted to be swung from wall to wall thereof, a latch borne by 40 said latch-body and designed to be moved by the latch-body into and out of engagement with the recess in the steering-post, a reciprocating fence, working in said latch-body, a bolt also working in said latch-body 45 and engaging with said fence, to secure the latch-body against either wall of the chamber, the tumbler-shaft provided with notched tumblers, engaging with the fence, the tubular shaft fitting on said tumbler-shaft, having notched tumblers also engaging with the fence, and dials on the outer ends of the said shafts, for reciprocating said fence, to move said latch into or out of engagement.

In testimony whereof I affix my signature 55 in presence of two witnesses.

JOHN R. HOUTS.
